UNITED STATES PATENT OFFICE.

WILLIAM SNEE, OF PITTSBURG, PENNSYLVANIA, ASSIGNOR OF PART TO
WILLIAM SMITH, OF SAME PLACE, CHARLES T. RUSSELL, OF ALLEGHENY, AND WILLIAM GUCKERT, OF PITTSBURG, PENNSYLVANIA.

STEAM-GENERATOR.

SPECIFICATION forming part of Letters Patent No. 404,740, dated June 4, 1889.

Application filed February 26, 1889. Serial No. 301,234. (No model.)

To all whom it may concern:

Be it known that I, WILLIAM SNEE, a citizen of the United States, and a resident of Pittsburgh, in the county of Allegheny and

5 State of Pennsylvania, have invented certain new and useful Improvements in Steam-Generators; and I do hereby declare that the following is a full, clear, and exact description of the invention, which will enable others skilled in the art to which it appertains to make and use the same, reference being had to the accompanying drawings, which form a part of this specification, and in which—

10 Figure 1 is a longitudinal sectional view on a vertical plane through the middle of my improved steam-generator, and Fig. 2 is a longitudinal transverse sectional view on line *x* *x* in Fig. 1.

Like letters of reference denote corresponding parts in both the figures.

15 My invention relates to safety-boilers or steam-generators, and it has for its object not only to provide for additional safety and absence of danger in that class of boilers, but also to economize fuel by extracting all the heat from the products of combustion before the same are finally permitted to escape through the chimney or smoke-stack.

With these objects in view my invention 20 consists in the improved construction and combination of parts of the steam-generator, which will be hereinafter more fully described and claimed.

In the accompanying drawings I have illustrated my invention as applied to a stationary boiler; but it is obvious that it is equally well adapted for use in locomotives or portable boilers generally.

25 The fire-box shown at A may be of any desired construction and adapted for any kind of fuel—such as coal, crude petroleum, natural gas, &c. It is located within the upright boiler B, so as to be surrounded by water on all sides except the bottom, and has in its top a goose-neck or curved flue C, which carries the heat and products of combustion into the heating-chamber D. The latter is in the nature of an oblong chamber of suitable length, height, and width, which in the case of stationary engines 30 may be built of brick and lined with fire-clay

or other refractory material, while in the case of locomotives or portable engines the walls of the heating-chamber D should be made of metal.

Arranged inside of the chamber D, in a line 55 with one another, are the heaters E, which may be constructed of boiler-iron, and are by preference cylindrical in shape, reaching from the bottom to the top of chamber D. This series of cylindrical heaters E are connected 60 to one another by pipes F, provided with cocks or valves G, for regulating or shutting off the flow of water through the series of heaters. Each heater is further provided with a diametrical flue H, so arranged as to alternate 65 with one another—that is to say, commencing with the heater E, nearest to the fire-box, the flue H, which passes through its center from one side to the other, is located near the bottom; in the heater next to this flue H is located near the top; in the heater following this flue H is again located near the bottom 70 in a line with the bottom flue of the first heater, and so on through the entire series of heaters until the last heater is reached, the 75 flue H of which opens up into the smoke-chamber I, from which the products of combustion are carried off through the smoke-stack J. By this arrangement it will be seen that by making chamber D of sufficient length, 80 and placing therein a sufficient number of heaters E, arranged as described, these heaters will have absorbed all the heat before the products of combustion escape into the smoke-chamber at the end of the series. In order 85 to retard the progress of the products of combustion and enable the several heaters to absorb their respective quota of heat, the chamber D is divided into sub-chambers or compartments K by means of side walls L, built 90 up between the heaters E and the sides of chamber D, as shown in Fig. 2 of the drawings. By this construction it will be seen that the products of combustion can only pass from one compartment K to another through the 95 flues H, which lead through the heaters.

I prefer to locate the feed-water tank M on top of chamber D, so as to still further utilize the heat of said chamber in heating the feed-water, which is then supplied to the heater E 100

farthest from the fire-box, by means of the feed-water pump N, in conjunction with the suction-pipe O and feed-pipe P.

Having thus described my invention, I claim
5 and desire to secure by Letters Patent of the
United States—

1. In a steam-generator, the combination of
the fire-box, the upright boiler within which
the same is located, the curved flue in the top
10 of the fire-box, the oblong heating-chamber
communicating at one end with said flue and
at the other end with the smoke-chamber, a
series of heaters located within said chamber
communicating with one another by pipes and
15 provided with diametrical flues located alter-
nately in the top and bottom part of said heat-
ers, and the side walls or partitions built up
between the sides of the several heaters and the
adjacent sides of the chamber within
20 which they are placed, substantially as and
for the purpose shown and set forth.

2. In a steam-generator, the combination of
the fire-box, the upright boiler within which
the same is located, the curved flue in the top

of the fire-box, the oblong heating-chamber 25
communicating at one end with said flue and
at the other end with the smoke-chamber, a
series of heaters located within said chamber
communicating with one another by pipes and
provided with diametrical flues located alter- 30
nately in the top and bottom part of said heat-
ers, the side walls or partitions built up between
the sides of the several heaters and the adj-
acent sides of the chamber within which they
are located, the feed-water tank on top of the 35
heating-chamber, the feed-water pump, and
the pipe connecting said pump with that one of
the heaters which is located farthest from the
fire-box, substantially as and for the purpose
shown and set forth. 40

In testimony that I claim the foregoing as
my own I have hereunto affixed my signature
in presence of two witnesses.

WILLIAM SNEE.
